GASEOUS ELECTRIC DISCHARGE DEVICE

Wilhelm Hagen, Berlin, and Wolfgang Thouret,
Berlin-Wilmersdorf, Germany, assignors to
General Electric Company, a corporation of New
York

Application January 11, 1937, Serial No. 120,066
In Germany January 15, 1936

1 Claim. (Cl. 176—126)

The present invention relates to gaseous electric discharge devices generally and more particularly the invention relates to vapor discharge lamp devices operating with elevated container 5 temperatures and with correspondingly elevated vapor pressures, such as a vapor pressure in the order of atmospheres, similar to those disclosed in co-pending application, Serial No. 104,312, filed October 6, 1936, the inventors being Marcello 10 Pirani, Robert Rompe and Wolfgang Thouret.

The gaseous electric discharge lamp devices disclosed in the co-pending application referred to above comprise a pair of electrodes centrally mounted in an elongated container and separated 15 a distance less than the diameter of the container. The current leads supporting the electrodes extend a substantial distance into the container, and consist of high melting point material such as tungsten or molybdenum. The container is of 20 small size and consists of a vitreous material, such as fused silica, capable of withstanding the high temperatures. Due to the different coefficients of expansion of the vitreous material and the metal it is desirable to use graded seals for 25 such devices.

The object of the present invention is to provide a gaseous electric discharge lamp device of the above type which comprises means of simple structure for protecting the part of the current 30 leads inside the lamp container from the effects of the gaseous electric discharge. Another object of the invention is to provide a gaseous electric discharge lamp device of the above type which is simple in structure and is inexpensive 35 to manufacture. Still further objects and advantages attaching to the device and to its use and operation will be apparent to those skilled in the art from the following particular description.

The invention attains its objects by surrounding 40 the internal part of the current lead with a tube or sleeve of high heat resisting, insulating material, such as quartz, the internal diameter of which closely approaches the diameter of the current lead extending therethrough to insure 45 protection of the current lead from the gaseous electric discharge. The lead protecting sleeve is part of the stem structure of the lamp which stem consists of the aforesaid sleeve, a graded joint fused to the end of and hermetically closing the 50 end of said sleeve and a current lead fused into said joint and extending through and beyond said sleeve. In the manufacture of the device the stem structure is first fabricated and the sleeve is then fused to the container to make an hermetic joint therein. The sleeve extends a substantial

distance into the container and terminates adjacent the electrode mounted on the end of the current lead.

We have observed that no diminution in the quantity of vaporizable material available for 5 the discharge takes place in a gaseous electric discharge lamp device embodying the present invention even after the device has been operating for several hundred hours. In many cases this is of importance, for example, when a limited 10 quantity of mercury is introduced into the lamp during the manufacture thereof in order to obtain an unsaturated vapor pressure when the lamp is at operating equilibrium. Any loss in the quantity of vaporizable material in the discharge chamber of a device so constructed would, of course, change the electrical characteristics of the device, which is undesirable. While this is apt to be a source of difficulty in devices 15 having protruding seals it does not take place in 20 devices embodying the present invention due to the fact that the electrode is closer to the end of the insulating sleeve than to the end of the container and consequently the end of the sleeve is at 25 a higher temperature during the operation of the 30 device than the end of the container. Any condensation of mercury vapor therefore takes place at the end of the container where it is available for the discharge rather than in the sleeve where it is not available for the discharge. 35

In the drawing accompanying and forming part of this specification a gaseous electric discharge lamp device embodying the invention is shown, in which

Fig. 1 is a side elevational view of a gaseous electric discharge lamp device, and

Fig. 2 is a sectional view of one end of the lamp shown in Fig. 1.

Referring to the drawing the gaseous electric discharge lamp device comprises an elongated, 40 tubular, quartz container 1 having a pair of current leads 4 sealed therein, one at each end thereof. Said current leads 4 consist of a high melting point material, such as tungsten. Said container 1 has therein a starting gas, such as 45 argon, and a quantity of vaporizable material, such as mercury, the vapor of which is luminosity producing during the operation of the device. An electrode 5 is mounted on each of said leads 50 4. Each of said electrodes 5 consists of a perforated, tungsten shell filled with a mixture of electron emitting materials, such as a mixture of aluminum oxide, tungsten and an alkaline earth oxide. Said electrodes 5 are heated to an electron

emitting temperature during the operation of the device by the discharge.

Said container 1 has a stem at each end thereof which stem consists of a quartz tube 2, 7, a graded seal 8, 9, 10, 11 fused to the end of said tube 2, 7 and to said current lead 4. The part 8 of said seal 8, 9, 10, 11 fused to said lead 4 consists of a glass having a coefficient of expansion approximating that of the tungsten lead 4 and the part 11 of said graded seal 8, 9, 10, 11 consists of a glass having a coefficient of expansion approximating that of the quartz tube 2, 7. The intermediate parts 9 and 10 of the seal have coefficients of expansion intermediate those of the parts 8 and 11. The part 7 of said tube 2, 7 extends from the end of said container 1 to a point adjacent the electrode 5 and has an opening 6 therein which is but slightly larger in diameter than the current lead 4 extending through said part 7. The part 2 of said tube 2, 7 extends a short distance beyond the end of the container 1 and has an opening 3 therein having the same diameter as the part 6 of the opening.

In the manufacture of the lamp device described above the stem consisting of the tube 2, 7, the seal 8, 9, 10, 11, the current lead 4 and the electrode 5 is first fabricated and the end of the container 1 is then fused to the tube 2, 7. The other steps in the manufacture of the lamp device, such as the treatment of the electrodes, exhausting the container and introducing the starting gas and the vaporizable material into the container, are then carried out.

The advantages of a gaseous electric discharge lamp device having the above structure have been pointed out above. It will be understood, of course, that numerous changes in the form and details of the device illustrated may be made within the scope of the appended claim, for example, the tube 2, 7 is wholly within the container 1 when desired. 5

What we claim as new and desire to secure by Letters Patent of the United States is:— 10

A gaseous electric discharge device comprising a vitreous container, electrodes and electrode leads sealed therein, a gaseous atmosphere therein, said container having a stem comprising an elongated tube of vitreous material fused thereto, 15 said tube surrounding one of said current leads and extending a substantial distance into said container, the coefficient of expansion of said tube being approximately equal to that of said container and being different than that of said current lead, the inner diameter of said tube being slightly larger than the diameter of said current lead, the external end of said tube being closed by a graded seal fused thereto and to said current lead, said current lead extending 20 along said tube and projecting beyond the internal end thereof, one of said electrodes being mounted on said current lead and adjacent the inner open end of said tube. 25
